Dec. 5, 1882

D

UNITED STATES PATENT OFFICE.

JAMES H. FLYNN AND JACOB A. SNELL, OF SCHENECTADY, NEW YORK.

DESIGN FOR A WHISK-BROOM CASE.

SPECIFICATION forming part of Design No. 13,468, dated December 5, 1882.

Application filed October 24, 1882. Term of patent 7 years.

To all whom it may concern:

Be it known that we, JAMES H. FLYNN and JACOB ARTHUR SNELL, citizens of the United States, residing at Schenectady, in the county of Schenectady and State of New York, have invented and produced a new and original Design for Whisk-Broom Cases, of which the following is a specification, reference being had to the accompanying illustration, forming part thereof.

A is the whisk-broom case, having the general form of the brush, open at the top and bottom. Bands *a a* are placed at the top and bottom, but may be omitted. Between the bands on the body of the case may be placed one or more ornaments, *b*.

B is the back of the whisk-broom case, made in the general form of a painter's pallet, and preferably of such dimensions that it projects beyond the case A, which is placed on the back B in such a position that the thumb-hole of the pallet is left uncovered and visible as shown. The back B may have on its surface one or more ornaments, *c*. The case A and back B are placed in such relative positions to each other that when the whisk-broom D is

placed in the case the back A forms a background, against which the shoulders of the whisk-broom are displayed, as shown.

We claim—

1. The design for a whisk-broom case herein shown, which consists in the case A, having bands *a a*, and the pallet-shaped back B.
2. The design for a whisk-broom case, which consists in the case A, having ornament *b* and the pallet-shaped back B.
3. The design for a whisk-broom case, which consists in the case A, having bands *a a*, ornament *b*, and pallet-shaped back B.
4. The design for a whisk-broom case, which consists in the case A, having bands *a a* and ornament *b*, and the pallet-shaped back B, having ornament *c*.
5. The design for a whisk-broom case herein shown and described, the same consisting of a pallet-shaped back, B, and case A.

JAMES H. FLYNN,
JACOB ARTHUR SNELL.
